HIGH FREQUENCY COUPLING SYSTEM

Daniel E. Harnett, Tuckahoe, N. Y., assignor to
Hazelton Corporation, a corporation of Delaware

Application May 31, 1934, Serial No. 728,438

26 Claims. (Cl. 178—44)

This invention relates to improvements in tuned high-frequency coupling systems, applicable to radio broadcast receivers, for selectively re-laying carrier wave signals.

5 An object of the invention is to provide a tuned coupling system, the selectivity or resonance band width of which is adjustable by means of a unitary control in such manner as to maintain the resonance band symmetrically disposed with respect 10 to the carrier frequency.

In the art of radio broadcasting speech and music, a high degree of selectivity or signal discrimination is, to a degree, incompatible with perfect reproduction of the originating acoustics. 15 Fidelity in reproduction of speech or music necessitates substantially uniform overall transmission of carrier frequency sidebands from approximately 50 cycles to between 5000 and 15000 cycles, depending upon the character of the program. 20 Where both upper and lower sidebands are transmitted the response characteristic of the receiver should be substantially uniform for double these values. It will be appreciated, however, that band widths of this order are not always obtainable 25 with freedom from interference due to stations operating on broadcasting channels adjacent the station selected, or from static.

At a particular reception locus and time, certain stations may be received substantially free 30 from interference while others may be subjected to the severe competition of powerful or nearby stations operating on adjacent channels. For receiving stations of the first type it is desirable that the selectivity of the receiver be decreased 35 in order that signal reproduction be made as perfect as the system is capable of providing. If, however, a shift in tuning is made to a station of the second type, it thereupon becomes highly desirable to sacrifice some tonal quality by increasing 40 the selectivity to the end of freedom from interference.

The present invention has for its primary object the provision of a tuned coupling system, applicable either to the reception frequency or intermediate frequency stages of a broadcast receiver, wherein the selectivity or resonance band width of the system may be adjusted as desired within limits, without necessity for retuning. As 45 applied more particularly to the intermediate frequency stages of a superheterodyne receiver, it is highly important that this change in selectivity be accomplished without shifting the resonance band in the frequency scale. To this end the present invention maintains the resonance band sym-

metrically disposed relative to the intermediate frequency as the selectivity is varied.

In a preferred embodiment the invention comprises in substance a plurality of like-constructed, singly resonant tuned circuits. These circuits are reactively coupled through capacity or inductance adjustable within limits such as optionally to change the overall selectivity from the narrow, single humped response, characteristic of optimum or less than optimum coupling between 10 tuned circuits, to the relatively broad, double-humped response, characteristic of over optimum coupling.

Some methods of varying the coupling between tuned circuits tend to shift the center or median 15 frequency of the band as the band width is altered. If the predominant portion of the selectivity of the receiver is shifted a like amount, the shift may be compensated by changing the setting of the main tuning control. Even though only a portion of the selectivity is varied by the coupling adjustments the shift in frequency may usually be compensated sufficiently for all practical purposes by readjusting the main tuning control. It is desirable, however, to be able to 20 tune the station in and then make appropriate 25 selectivity adjustment without having to reset the tuning; in other words, to make the tuning and selectivity tuning controls independent of each other.

A feature of the present invention resides in the association with the individual resonant circuits constituting each coupling system, of compensating reactances responsive to variation of coupling therebetween for maintaining the resonance band disposed, as stated, in substantial 35 symmetry to the reception or intermediate frequency as the case may be. These compensating reactances may take the form of adjustable reactances in series with, or in shunt to, the principal tuning reactances of the coupled circuits. Where the resonance band width is adjustable 40 in steps, these compensating reactances may be semi-adjustable elements which are suitably adjusted once for all in relation to their associated 45 coupling reactance. Or, in the quantity production of radio receivers, the compensating and coupling reactances may be permanently fixed in value as determined by the receiver design.

On the other hand where, as is the case in accordance with one modification of the present invention, a capacitive coupling between tuned 50 circuits is employed which is continuously adjustable throughout a range of values, it is desirable that the corresponding compensating 55

capacities should likewise be so continuously varied by the coupling adjustment as to prevent substantial shifting in frequency of the resonance band. As a further feature of novelty, the present invention provides a continuously variable condenser of original construction adapted to achieve this objective.

Referring now to the drawings:

Fig. 1 shows diagrammatically as applied to a radio broadcast receiver, tuned coupling systems in accordance with the present invention employing capacitive coupling and compensating capacitive reactances adjustable in steps by a unitary control.

Fig. 2 depicts the symmetrical disposition of the resonance band with respect to the median frequency as its width is varied in accordance with the invention.

Fig. 3 is a modification of the Fig. 1 coupling system.

Figs. 4 and 5 show coupling systems wherein the resonance band width is adjustable in steps by means of inductive rather than capacitive reactances.

Fig. 6 illustrates diagrammatically, application of the novel variable condenser structure herein to a second type of capacitively coupled system, for continuously adjusting the band width while preventing substantial shifting of the band in the frequency scale.

Fig. 7 is a simplified coupling system generic to the modifications of Figs. 1, 3, 4, and 5.

Fig. 8 is a generic simplified circuit diagram embracing the Fig. 6 type of coupling system.

Fig. 9 is a front elevation of the novel condenser structure illustrated diagrammatically in Fig. 6, a portion of the structure being broken away to show the assembly.

Fig. 10 is a section along 10—10 of Fig. 9.

Fig. 11 is a circuit diagram, similar to that of Fig. 6 of a coupling system employing a condenser structure similar to that of Figs. 9 and 10 but provided with additional stator and rotor plates.

Fig. 12 is a view in sectional elevation, corresponding to Fig. 10, of the condenser structure illustrated diagrammatically in Fig. 11.

Referring to Fig. 1, there are shown an antenna 1 and ground 2, constituting the input to a superheterodyne radio broadcast receiver, wherein the radio frequency stages and the oscillator-modulator portion of the system are shown diagrammatically by the rectangle 3. The modulator anode (not shown) is connected by lead 4 to the upper terminal of a coil L_x' , the lower terminal of which is grounded at 5 through the modulator plate battery 6. The modulator cathode (not shown) is effectively grounded at 1, so that the modulated output is impressed across coil L_x' . Coil L_x' constitutes the input to a tuned coupling system T_1 in accordance with the present invention and described more fully hereinafter, the output of which comprises a similar coil L_y' connected between ground 8 and the grid G_1 of a vacuum tube V_1 operating as a stage of intermediate frequency amplification. The cathode of tube V_1 is effectively grounded through the biasing impedance 9.

A coupling system T_2 similar to T_1 relays the signals from the output of tube V_1 to the input of a second stage of intermediate frequency amplification, tube V_2 . To this end the anode A_2 of tube V_1 is connected by lead 10 to the upper terminal of an input coil L_x similar to L_x' , the lower terminal of which is grounded at 11

through the plate battery 12 supplying tube V_1 . Output coil L_y of system T_2 is connected between ground 13 and over lead 14 to the grid G_2 of tube V_2 , the cathode K_2 of which is grounded through the biasing impedance 15.

The signal voltage developed between the anode A_2 and grounded cathode K_2 of tube V_2 is applied by way of connections 16 and 17 to the portion of the receiver comprising the detector and audio frequency amplifier indicated diagrammatically by rectangle 18, the output of which extends to the usual loud speaker 20.

The coupling system T_2 of Fig. 1 comprises, in addition to the input and output coils L_x and L_y , a pair of tuning condensers C_x and C_y , connected to the coils respectively, and several additional condensers C_a , C_b , and C_c associated with contacts of a two-position gang switch H_2 . The connections are such that operation of the switch arm H_2 to contacts m , connects condensers C_a and C_c in series respectively with condensers C_x and C_y across the respective coils L_x and L_y . Operation of the switch to position n , disconnects condensers C_a and C_c and substitutes therefor a common coupling condenser C_b interposed between the grounded terminals of coils L_x and L_y and the tuning condensers C_x and C_y , being thereby serially included in each of the parallel resonant circuits L_x , C_x and L_y , C_y .

The resonant circuits L_x , C_x , C_a and L_y , C_y and C_c resulting from operation of switch H_2 to position m , are loosely coupled capacitively, inductively, or by a combination of the two, due to their exposed proximity, as is indicated at M. For the latter condition coils L_x and L_y are preferably so poled that the inductive coupling aids the capacitive coupling to give the resulting coupling M . If the inductive coupling is made to oppose the capacitive coupling, the latter must be sufficiently large to assure the desired degree of resulting coupling M . Coupling M , being less than optimum, provides a single humped, sharply peaked resonance characteristic for this system, such as is illustrated by curve k of Fig. 2.

With switch H_2 operated to contacts n , condensers C_a and C_c are, as stated, replaced by the single coupling condenser C_b , common both to the input L_x , C_x and output L_y , C_y circuits of the coupling system. Condenser C_b is of such magnitude as to produce the relatively broad, double humped, resonance for the coupling system, such as characterizes over optimum coupling illustrated by curve l of Fig. 2.

In order to assure that the resonance bands l and k , Fig. 2, will be symmetrically disposed relatively to the intermediate frequency f , for both positions of switch H_2 , the following preliminary adjustments are made: with the switch in position n , the coupling condenser C_b is adjusted to give the desired over optimum coupling, curve l , assuring a broad band width for high fidelity in reproduction in the absence of interference. Condensers C_x and C_y are then varied to allocate the intermediate frequency f substantially at the center of the resonance band. Switch H_2 is then shifted to position m , to provide the highly selective resonance band, curve k , and condensers C_a and C_c varied to dispose this narrow resonance band symmetrically with respect to the intermediate frequency f .

Condenser 21, interposed between coil L_x and ground 13, is of a sufficiently large capacity not to enter into the high frequency operation of the system. It is merely a blocking condenser which serves to prevent short circuiting the grounded

plate voltage 12 supplying tube V_1 , and also to isolate this plate voltage from the grid of tube V_2 likewise grounded at 13 through coil L_y .

In the event that it is desired to apply automatic volume control to the grid of tube V_2 , a second blocking condenser will be required in the connection 22 extending from the lower terminal of coil L_y and ground 13. The precise connections for this are illustrated as applied to coupling system T_1 . An automatic control biasing connection extends from the rectifier output over conductor 23 to the grid of tube V_1 through coil L_y' . The alternating current components of the biasing voltage thus applied are filtered out to ground at 8 through the blocking condenser 24 of coupling system T_1 . Blocking condenser 25 isolates battery 6 from ground 8.

Coupling system T_1 is in all respects identical in construction and operation with T_2 and may be actuated by a unitary control U , simultaneously and similarly to adjust both coupling systems either to the narrow response, curve k , or to the broad response, curve l . For the latter condition the common coupling condensers C_b and C_b' should be so selected that the maximum coupling does not greatly exceed the over optimum condition unless precautions are taken to reduce the tendency of the resulting peaks in the overall response curve to emphasize the extreme modulation frequencies. If, however, this condition is found to be present with the desired coupling, it may be minimized or eliminated by employment of suitable terminating resistances connected in shunt to or included in coils L_x' , L_y' , etc., in accordance with well understood filter theory. Alternatively a third coupling system permanently adjusted to the narrow response, curve k , might be associated with the output of tube V_2 , and adjusted so that the peak of curve k provided by this coupling will fill out the depressions occurring between the peaks, curve l , in the response produced by couplings T_1 and T_2 .

The coupling system of Fig. 3, which is of the same type as that of Fig. 1, provides three adjustments in band width, effected by actuating the gang switch H to positions m , o , and n . With the switch in position m , the tuning condensers C_x and C_y are connected in series with condensers C_a and C_c respectively, across the respective coils L_x and L_y . With the switch adjusted to position o , the tuning condensers C_x and C_y are connected in series respectively with condensers C_a and C_c and thence through the common coupling condenser C_r to ground at 13. With the switch in position n , the tuning condensers C_x and C_y are grounded only through the common coupling condenser C_b .

Adjustment of this system is analogous to that described in connection with the system of Fig. 1. With the switch in position n , condenser C_b is adjusted to give the desired maximum or over optimum coupling, and condensers C_x and C_y adjusted symmetrically to dispose the resonance band relative to the intermediate frequency. With the switch in position m for loose or less than optimum coupling, condensers C_a and C_c are adjusted to tune the system to the carrier frequency. With the switch in position o , condenser C_r is adjusted to give a desired coupling intermediate to that of switch positions m and n , and condensers C_a and C_c varied to tune the system to the intermediate frequency.

The Fig. 3 type of coupling system as well as those described below may be employed in a receiver such as is illustrated in Fig. 1, by connect-

ing lead 14 to the grid of a succeeding tube, and leads 10 and B_+ to the anode and plate supply respectively of a preceding tube in the manner illustrated in Fig. 1.

Figs. 4 and 5 show coupling systems wherein the resonance band width is adjustable in steps by means of inductances such as L_a - L_c incl., replacing capacities such as C_a - C_c incl. in the Fig. 1 coupling system.

Referring to Fig. 4, operation of switch H to position m connects coils L_x and L_a in series across condenser C_x , and coils L_y and L_c in series across condenser C_y . The coupling between coils L_x and L_y , or between coils L_a and L_c , or between both mentioned pairs of coils, is then adjusted to give the desired value to provide the narrow band resonance, such as curve k of Fig. 2. With the switch thrown to position n to replace coils L_a and L_c by the common coupling coil L_b , the latter is adjusted to the desired value for the expanded or over optimum coupled condition of curve l , Fig. 2. Condensers C_x and C_y are then adjusted properly to center the band with respect to the carrier frequency f , Fig. 2. The switch is again thrown to position m and the narrow band resonance properly centered with respect to the carrier frequency by adjustment of coils L_a and L_c .

Fig. 5 shows the Fig. 4 coupling system as modified by the employment of a two-winding coupling transformer L_c' , the low potential terminals of which are connected through a blocking condenser 21 serving to isolate from the secondary circuit L_y , C_y the plate voltage applied over the B_+ lead to the primary circuit L_x , C_x . Otherwise the construction and adjustment of the Fig. 5 circuit is similar to that of Fig. 4.

In the quantity production of radio receivers employing coupling systems like those of Figs. 4 and 5, coils L_a , L_b and L_c or L_c' would normally be adjustable only in an experimental model for purposes of determining the proper settings. The usual commercial tolerances are close enough so that the inductances of these coils would not require adjustment as to each receiver.

Fig. 6 illustrates diagrammatically a coupling system employing a variable condenser D of unique construction adapted to vary the resonance band width by continuous gradations while maintaining the band symmetrically disposed with respect to the carrier frequency in the manner of curves k and l , Fig. 2. This condenser, the mechanical assembly of which, Figs. 9 and 10, is described below, is shown diagrammatically in Fig. 6, by the spaced plates q , r , s , t , u inclusive. Plates r and t which are insulatedly mounted stator plates, interleave respectively, variable plates q , s and u , indicated in Fig. 6 for clarity of explanation as being vertically adjustable, whereas as mechanically embodied, Figs. 9 and 10, these plates are rotatable in a manner explained below.

The coupling system is formed by joining stator plate r to the high-potential terminal of a resonant input circuit comprising coil L_x shunted by a tuning condenser C_x , the low-potential end of which is grounded at 13 through blocking condenser 21. Stator plate t is joined to the high-potential terminal of a resonant output circuit comprising a coil L_y shunted by a tuning condenser C_y , the low-potential end of which is likewise grounded at 13. Rotor plates q , s and u are conductively joined by a conductor 26 grounded at 21.

It will be observed that the capacity present

between stator plates r and t forms a capacitive coupling C_{r-t} serially interposed between the tuned parallel resonant circuits $L_x C_x$ and $L_y C_y$. The magnitude of this coupling depends upon the extent to which the interposed, grounded, vertically adjustable plate s , interleaves stator plates r and t . The capacities C_{q-r} and C_{r-s} , determined by the overlapping of adjustable plates q and s and stator plate r , are effectively in parallel to each other and to the tuning condenser C_x . Similarly the capacities C_{s-t} and C_{t-u} between the adjustable plates s and u and the stator plate t respectively, are in parallel to each other and to the tuning capacity C_y .

If now it be assumed that the capacity C_{r-t} is increased but without changing the direct capacity from plates r and t to ground, the coupling C_{r-t} will increase with consequent broadening of the resonance band, the latter becoming double humped as optimum coupling is passed. This broadening of resonance will, however, be accompanied by a shifting of the resonance band toward lower frequencies. If, however, this increase in C_{r-t} is accomplished by the downward movement of plate s there will be a consequent decrease in the capacities C_{r-s} and C_{s-t} , the effect of which tends to shift the center of the resonance band toward the higher frequencies. Since the spacing between the plates $r-s$ and $s-t$ is less than the spacing between plates r and t , the latter effect will predominate, and the resulting shift in the center of the resonance band will be toward the higher frequencies.

On the other hand, simultaneous vertical movements of plates q and u to increase the capacities C_{q-r} and C_{u-t} will tend to shift the resonance band toward lower frequencies. Therefore, if plates q and u are properly spaced in relation to plates r and t respectively, and are further moved simultaneously with plate s , as by employing a rigid connection 26, the tendency toward a shifting of the resonance band in frequency caused by movement of plate s , may be substantially compensated throughout the condenser range, by the opposite tendency resulting from the simultaneous movement of plates q and u . In this way the width of the resonance band may be varied without any substantial shifting of its median frequency.

As mechanically embodied, Figs. 9 and 10, condenser D is of rotary interleaving plate construction. Stator plates r and t are insulatedly supported on rods 36, 37 and 38, 39, respectively, extending in insulated relation through relatively large apertures 40 of housing 41, and thence through insulating side blocks, such as 42, 43 and 44, riveted to opposite outer surfaces of the housing as shown. Rotor plates q , s and u are conductively mounted on a rotatable shaft 45, projecting through apertures of the housing 41 to provide bearing supports. The rotor and stator plates are of the conventional semi-circular configuration, with rotor plate s oppositely disposed on shaft 45 to the aligned rotor plates q and u .

For purposes of varying the resonance band without appreciably shifting the median frequency, the spacing between plates q , r and t , u will normally be greater than that between r , s and s , t . The same results may, however, be achieved by employing any reasonable spacing and so shaping the rotor plates as to secure the desired individual variations.

Capacity variations such as C_{q-r} , C_{r-s} , etc. of Fig. 6, may be obtained with a condenser employing a plurality of plates corresponding to each

of the plates q , r , s , t and u shown in the Fig. 10 construction. Figs. 11 and 12 corresponding respectively to Figs. 6 and 10, illustrate how this extension may be effected. In Figs. 11 and 12, the plate groups $q_1, q_2; r_1, r_2, r_3; s_1, s_2, s_3; t_1, t_2, t_3$; and u_1, u_2 , replace the individual plates q , r , s , t and u respectively of Figs. 6 and 10.

Operation of the Fig. 11 coupling system is the same as that described for the Fig. 6 system. In Fig. 11 the capacity C_{q-r} represents the sum of the capacities present between plates $q_1, r_1; r_1, q_2$; and q_2, r_2 ; capacity C_{r-s} is the sum of the capacities between plates $r_2, s_1; r_3, s_2$; and r_3, s_3 ; the capacity C_{r-t} is that between plates $r_2, t_1; r_3, t_1$; and r_3, t_2 ; the capacity C_{s-t} that between plates $s_1, t_1; s_2, t_1$; and s_3, t_2 ; and the capacity C_{u-t} that between plates $t_2, u_1; t_3, u_1$; and t_3, u_2 .

The coupling systems of Figs. 1, 3, 4, and 5 are of the type generically illustrated in Fig. 7, wherein the common coupling impedance Z_b is serially included in each of the parallel resonant side circuits $L_x C_x$ and $L_y C_y$. Increasing the reactance of Z_b , therefore, increases the coupling and tends increasingly to connect the two side circuits $L_x C_x$ and $L_y C_y$ in series with each other. In order to secure the relatively narrow band selectivity of Fig. 2, impedance Z_b would, at the tuned frequency, normally be relatively small in comparison with the component tuning impedances of the side circuit reactances. Thus if Z_b is an inductance, it would normally be small in comparison with L_x and L_y , and if a capacity, it would normally be large in comparison with C_x and C_y .

The coupling systems of Figs. 6 and 11, on the other hand, are of the type illustrated generically in Fig. 8, wherein the coupling impedance Z_b is serially interposed between the parallel resonant side circuits $L_x C_x$ and $L_y C_y$. It will be evident that as Z_b is decreased the side circuits $L_x C_x$ and $L_y C_y$ are coupled increasingly in parallel with each other. For this case the impedance Z_b is, at the tuned frequency, normally large in comparison with the component side circuit reactances. Thus if Z_b is an inductance adapted to provide the relatively narrow band selectivities of Fig. 2, it should be large in comparison with the inductances L_x and L_y , and if a capacity, it should be small in comparison with C_x and C_y .

In applying a plurality of coupling systems such as those of Figs. 6 and 11 to a radio broadcast receiver such as Fig. 1, the rotor elements of all of condensers D are preferably manipulated by a unitary control. That is, referring to Figs. 10 and 12, the rotor elements of the several coupling condensers would be mounted on the common shaft 45.

The coupling systems described herein are not restricted as to the number of resonant or tuned circuits that may be employed in each. Although the specific illustrations are those wherein a pair of resonant circuits are coupled in accordance with the various modifications of the present invention, the same principles apply in combining three, four or more tuned circuits in each coupling system.

I claim:

1. A high frequency coupling system comprising a plurality of reactively coupled resonant circuits including reactance means of opposite types and tuned to a selected frequency, means for adjusting the reactive coupling between said circuits to vary the resonance band width of said

- system and for simultaneously altering the reactance value of reactance means of a given type electrically independent and individual to said circuits to prevent shifting of the resonance band in the frequency scale.
5. A high frequency coupling system comprising a plurality of reactively coupled resonant circuits including reactance means of opposite types and tuned to a selected frequency, means for adjusting the reactive coupling between said circuits to vary the resonance band width of said system by continuous gradations and for simultaneously altering the reactance value of reactance means in each of said circuits to prevent shifting of the resonance band in the frequency scale.
10. A high frequency coupling system comprising a plurality of reactively coupled resonant circuits including reactance means of opposite types and tuned to a selected frequency, means for adjusting the reactive coupling between said circuits to vary the resonance band width of said system to one of at least three different values and for simultaneously altering the reactance value of reactance means in each of said circuits to prevent shifting of the resonance band in the frequency scale.
15. A high frequency coupling system comprising a plurality of reactively coupled resonant circuits including reactance means of opposite types and tuned to a selected frequency, means for adjusting the reactive coupling between said circuits to vary the resonance band width of said system to a selected frequency, means for adjusting the reactive coupling between said circuits to vary the resonance band width of said system to one of at least three different values and for simultaneously altering the reactance value of reactance means in each of said circuits to prevent shifting of the resonance band in the frequency scale.
20. A high frequency coupling system comprising a plurality of resonant circuits, each containing inductance and capacitance and tuned to a selected frequency, said circuits being capacitively coupled, means for adjusting the capacitive coupling between said circuits to vary the resonance band width of said system and for altering only the capacitance of each of said circuits by substituting for capacitance thereof capacitance of a different value so as to prevent simultaneous shifting of the resonance band in the frequency scale.
25. In a high frequency coupling system comprising a plurality of resonant circuits, each containing inductance and capacitance and tuned to a selected frequency, said circuits being inductively coupled, means for adjusting the inductive coupling between said circuits to vary the resonance band width of said system and for altering only inductance of each of said circuits by substituting therefor inductance of a different value so as to prevent simultaneous shifting of the resonance band in the frequency scale.
30. In a high frequency coupling system comprising a plurality of resonant circuits, each containing inductance and capacitance and tuned to a selected frequency, said circuits being inductively coupled, means for adjusting the inductive coupling between said circuits to vary the resonance band width of said system and for altering only inductance of each of said circuits by substituting therefor inductance of a different value so as to prevent simultaneous shifting of the resonance band in the frequency scale.
35. A high frequency coupling system tuned to a selected frequency comprising: a plurality of reactively coupled resonant circuits, a plurality of supplemental coupling reactances and associated switching means for adjusting said coupling in steps, and supplemental reactances individual to said resonant circuits selectively connectible thereto by said switching means to prevent shifting of the resonance band in the frequency scale with adjustment of said coupling.
40. A high frequency coupling system tuned to a selected frequency comprising: a plurality of reactively coupled resonant circuits each containing inductance and capacity, a plurality of coupling capacities and associated switching means for adjusting said coupling in steps, and supplemental capacities individual to said resonant circuits selectively connectible thereto by said switching means to prevent shifting of the resonance band in the frequency scale with variation in coupling.
45. A high frequency coupling system tuned to a selected frequency comprising: a plurality of reactively coupled resonant circuits each containing inductance and capacity, a plurality of coupling capacities and associated switching means for adjusting said coupling in steps, and supplemental capacities individual to said resonant circuits selectively connectible thereto by said switching means to prevent shifting of the resonance band in the frequency scale with variation in coupling.
50. A high frequency coupling system tuned to a selected frequency comprising: a pair of parallel resonant circuits containing a common coupling inductance serially included in each circuit, each said resonant circuit containing an individual and electrically independent tuning inductance which is relatively large compared to said coupling inductance, and means for adjusting said coupling inductance to vary the resonance band width of said system and simultaneously adjusting said individual inductances to prevent shifting of the resonance band in the frequency scale.
55. A high frequency coupling system comprising a pair of parallel resonant circuits containing a common coupling inductance serially included in each circuit, each said resonant circuit containing an individual and electrically independent tuning inductance which is relatively large compared to said coupling inductance, and means for adjusting said coupling inductance to vary the resonance band width of said system and simultaneously adjusting said individual inductances to prevent shifting of the resonance band in the frequency scale.
60. A high frequency coupling system comprising a pair of parallel resonant circuits serially connected through a common coupling reactance, said coupling reactance being relatively large compared to component tuning reactances of said resonant circuits, and means for adjusting said coupling reactance to vary the resonance band width of said system and simultaneously adjusting a component reactance of each of said resonant circuits to prevent shifting of the resonance band in the frequency scale.
65. A high frequency coupling system comprising a pair of parallel resonant circuits serially connected through a common coupling capacity, the tuning capacity of each said circuit being large relative to said coupling capacity, and means for adjusting said coupling capacity to vary the resonance band width of said system and simultaneously adjusting said resonant cir-

cuit capacities to prevent shifting of the resonance band in the frequency scale.

15. A high frequency coupling system tuned to a selected frequency comprising: an interleaving plate condenser consisting of a plurality of aligned stators having certain of their plates mutually exposed capacitively, a rotor common to said stators provided with aligned plates interleaving the mutually exposed stator plates, and 10 angularly displaced therefrom on a common shaft other aligned plates capacitively coupled only to plates of the respective stators, a plurality of resonant circuits connected respectively between said stators and the rotor, said rotor and stator plates being so spaced and the said rotor plates so angularly displaced that adjustment of the rotor varies the resonance band width of said system while preventing shifting of the resonance band in the frequency scale.

20. 16. A high frequency coupling system tuned to a selected frequency comprising: an interleaving plate condenser consisting of a pair of aligned stators having certain of their plates mutually exposed capacitively, and a rotor including 25 aligned plates interleaving the exposed stator plates, and angularly displaced therefrom on a common shaft other aligned plates capacitively coupled only to plates of the respective stators, a pair of resonant circuits connected respectively 30 between said stators and the rotor, said rotor plates being so disposed and spaced that adjustment of the rotor varies the resonance band width of said system while preventing shifting of the resonance band in the frequency scale.

35. 17. A high frequency coupling system tuned to a selected frequency comprising: an interleaving semi-circular plate condenser consisting of a pair of aligned stators having certain of their plates mutually exposed capacitively, and a rotor having 40 aligned plates interleaving the exposed stator plates, and oppositely displaced therefrom on a common shaft other aligned plates capacitively coupled only to the plates of the respective stators, a pair of resonant circuits connected respectively 45 between said stators and the rotor, said rotor and stator plates being so spaced that adjustment of the rotor varies the resonance band width of said system while preventing shifting of the resonance band in the frequency scale.

50. 18. A high frequency coupling system tuned to a selected frequency comprising a variable interleaving plate condenser consisting of a rotor having a pair of aligned plates angularly displaced on a shaft with respect to an intermediate plate, and a pair of insulatedly supported stator plates spaced to interleave the rotor plates, and a pair 55 of resonant circuits connected respectively between the stator plates and the rotor, said plates being so spaced, shaped and angularly displaced that adjustment of the rotor varies the resonance band width of said system while preventing shifting of the resonance band in the frequency scale.

55. 19. A high frequency coupling system tuned to a selected frequency comprising: an interleaving semi-circular plate condenser comprising a rotor consisting of a pair of aligned plates angularly displaced on a conductive shaft with respect to an intermediate plate, a pair of insulated stator plates spaced to interleave the rotor plates, a pair 60 of resonant circuits connected between the respective stator plates and the rotor, said rotor and stator plates being so spaced and the said rotor plates being so angularly displaced that adjustment of the rotor varies the resonance band

width of said system while preventing shifting of the resonance band in the frequency scale.

20. In a high frequency coupling system comprising two resonant circuits tuned to a selected frequency and adapted to be adjustably coupled to permit variation of the resonance band width of said system without shifting the resonance band in the frequency scale, a variable coupling condenser therefor of rotary interleaving plate construction comprising: a plurality of insulatedly supported aligned stators having certain of their plates mutually exposed capacitively, a rotor common to said stators provided with aligned plates interleaving the mutually exposed stator plates, and angularly displaced therefrom on a common shaft other aligned plates capacitively coupled only to plates of the respective stators, the rotor and stator plates being so spaced and shaped and the said rotor plates being so angularly displaced that adjustment of the rotor to increase the capacity between said stators decreases in a definite relation thereto the capacities between the rotor and the respective stators.

25. 21. In a high frequency coupling system comprising two resonant circuits tuned to a selected frequency and adapted to be adjustably coupled to permit variation of the resonance band width of said system without shifting the resonance band in the frequency scale, a variable coupling condenser therefor of rotary interleaving plate construction comprising: a pair of insulatedly supported aligned stators having certain of their plates mutually exposed capacitively, a rotor common to said stators provided with aligned 30 plates interleaving the mutually exposed stator plates, and angularly displaced therefrom on a common shaft other aligned plates capacitively coupled only to plates of the respective stators, said rotor and stator plates being so spaced and the said rotor plates being so angularly displaced 35 that adjustment of the rotor varies the capacities between said stators in definite relation to the capacities between the rotor and the respective stators.

40. 22. In a high frequency coupling system comprising two resonant circuits tuned to a selected frequency and adapted to be adjustably coupled to permit variation of the resonance band width of said system without shifting the resonance band in the frequency scale, a variable coupling condenser therefor comprising: a rotor having a pair of aligned plates angularly displaced on a common shaft with respect to an intermediate plate, and a pair of insulatedly mounted stator plates interleaving the rotor plates, said rotor and stator plates being so spaced and shaped and the said rotor plates being so angularly displaced that adjustment of the rotor to increase capacity between the stator plates decreases in a definite relation thereto the capacities between the rotor and the respective stator plates.

45. 23. A high frequency coupling system comprising a plurality of reactively coupled resonant circuits including reactance elements of opposite types and tuned to a selected frequency, means for adjusting the reactive coupling between said circuits to vary the resonance band width of said system and for simultaneously substituting for a 50 reactance element of each of said circuits a reactance element of the same type and of a different value to prevent shifting of the resonance band in the frequency scale by the adjustment of said coupling.

24. A high frequency coupling system comprising a plurality of reactively coupled resonant circuits including reactance means of opposite types and tuned to a selected frequency, means for 5 adjusting the reactive coupling of only one type between said circuits to vary the resonance band width of said system and for simultaneously altering the reactance value of reactance means, of the same type as said adjusted coupling reactance, 10 in each of said circuits, to prevent shifting of the resonance band in the frequency scale by the adjustment of said coupling.

25. A high frequency coupling system comprising: a plurality of resonant circuits including reactance elements of opposite types tuned to a selected frequency and coupling reactance of a given type coupling said circuits, means for adjusting the resonance band width of said system comprising means for substituting for a coupling 15 reactance element in at least one of said circuits a

reactance element of the same type but providing a different value of reactance in said circuit, said substituted element being individual to said one of said circuits, whereby shifting of the resonance band in the frequency scale by the adjustment of 5 said coupling is prevented.

26. A high frequency coupling system comprising: a plurality of resonant circuits each containing inductance and capacitance and tuned to a selected frequency, coupling inductance coupling 10 said circuits, means for adjusting the resonance band width of said system comprising means for substituting for a coupling inductance element in at least one of said circuits a supplemental inductance providing a different value of reactance 15 in said circuit, whereby simultaneous shifting of the resonance band in the frequency scale is prevented.
